(57) CLAIM

The ornamental design for a jar of candy, as shown and described.

DESCRIPTION

FIG. 1 is a perspective view from the front and right side of a jar of candy, showing my new design;

FIG. 2 is an elevational view from the right side thereof;

FIG. 3 is a rear elevational view thereof;

FIG. 4 is a top plan view thereof; and,

FIG. 5 is a bottom plan view thereof.

The broken line showing of the environment is for illustrative purposes only and forms no part of the claimed design.
